CIRCUIT BREAKER

Filed Nov. 18, 1935

FIG. 1.

UNITED STATES PATENT OFFICE

2,099,639

CIRCUIT BREAKER

Joseph D. Wood, Bethlehem, Pa., assignor to
Roller-Smith Company, a corporation of New
York

Application November 18, 1935, Serial No. 50,299

5 Claims. (Cl. 200—146)

This invention relates to circuit breakers and more particularly to an improved method and structure for reducing the arcing upon opening the contacts of oil circuit breakers.

5 The present invention is shown applied to the form of contacts disclosed in my prior Patent No. 1,974,525, granted September 25, 1934 but may be embodied in other structures than the particular form shown.

10 One object of the present invention is to cause the breaking of the arc under a reduced distance of opening movement of the contacts. Another object is to reduce the tank pressure upon the opening of the breakers. Another object is to re-

15 duce the burning of the contacts and to reduce the deterioration of the breaker to a minimum. Another object is to quickly quench the arc upon the opening of the breaker and to increase the safety factors. Another object is to produce a

20 simple, dependable and durable form of construction for accomplishing the above objects. Other objects and advantages of this invention will be understood from the following description and accompanying drawing which show a preferred embodiment.

Fig. 1 is a side view of a pair of circuit breaker contacts with a bridging member partly in section and showing the oil tank in section, the breaker being shown in an opening position;

30 Fig. 2 is a plan view of cooperating contacts on the line 2—2 of Fig. 1 and showing the parts in closed position; and

Fig. 3 is a side view of cooperating contacts shown in closed position.

35 Referring to Fig. 1, the usual tank 5 surrounds the contacts of the breaker and contains oil maintained at a desirable level to cover the contacts. Only one set of contacts is shown, but it will be understood that any number thereof may be used 40 and their movement controlled in any way desired. A pair of insulators 6 is supported in the top portion of the tank and envelop the conductors leading to the main contacts 7. These contacts are laminated and flexible to insure good 45 contact with the bridging member. The contacts 7 are bent and pressed against plates 8 and are clamped in place by the plates 9, the parts being held together immediately below the insulators 6 by bolts and nuts 10.

50 An auxiliary fixed arcing contact of metal is also clamped to each main contact at its upper end by the bolts and nuts 10, each of these auxiliary contacts being held in place on the outside of each clamp 8. Each auxiliary arcing member 55 has a main portion 11 extending downwardly and on its outer lower end has an outwardly projecting arcing contact portion 12. The portion 12 may be integral with the portion 11 or secured thereto by screws 12a. These auxiliary contacts 60 extend below the main contacts 7 and are spaced

outwardly from them as shown in Fig. 1. The lower inside surface of each auxiliary contact is rounded to form a contact surface engaged by the auxiliary movable contact. The portion 12 of each auxiliary contact is rounded at its upper outer part 13 and forms a projection from the part 11 for the final path of the arc.

5 The bridging conducting member 14 is of inverted U-shaped form and is suitably secured to the upwardly extending operating rod 15 of 10 suitable insulating material. The top surface of the bridging member 14 is adapted to engage the laminated main contacts 7 when raised to closed position.

15 The upper outer ends of the bridging member 14 are cut away to form a pair of outwardly extending ears 14a at each end. Between these ears is mounted a rod 16 at each end of the bridging member. Upon each of the rods 16 is pivotally mounted an auxiliary movable contact 20 element 17. This may be a solid piece of metal or made up of two or more pieces clamped together. Its upper outer portion is rounded as shown at 17a so that when the bridging member 25 is raised for closing the contacts, the rounded portion 17a of each auxiliary movable contact 30 will engage the rounded lower inner portion of each of the auxiliary fixed contacts 11. The auxiliary movable contacts 17 are provided at 35 each of their ends with an outwardly extending plate or flange 17b. These projecting side portions are adapted to embrace the lower portion of the auxiliary fixed contacts when in closed position, as shown in Figs. 2 and 3. Pins 18 pass through downward extensions 17c from each of 40 the auxiliary contacts 17 and extend outwardly to serve as a stop for limiting the outward movement of the contacts by engaging the lower edges of the bridging member 14, as shown in Fig. 1. A spring 19 is connected at one end to the pin 45 18 and at its other end to a pin 18a extending between the sides of the bridging member. The auxiliary contacts 17 are thus biased to move outwardly toward the position shown in Fig. 1. A flexible conductor 20 is secured at one end to 45 the bridging conductor and at the other end to the auxiliary contact 17 to form good electrical connection between the bridging conductor and its auxiliary contacts.

50 In operation, when the breaker is closed, the 50 bridging member 14 is moved upwardly by the rod 15 causing the auxiliary contacts 17 to first engage at the rounded portions 17a with the rounded portions of the auxiliary fixed contacts 12. As the breaker continues the closing movement, the auxiliary contacts 17 are moved inwardly against the pressure of the springs 19 and slide up against the inner surfaces of the fixed auxiliary contacts as the bridging member 14 engages the main contacts 7. In the closed 55 60

position, as shown in Fig. 3, the side extensions 17b of the auxiliary movable contacts embrace the lower ends of the auxiliary fixed contacts.

When the breaker is moved to the open position by the downward movement of the rod 15, the current is first ruptured between the main contacts 7 and the bridging member 14, the current continuing to pass through the auxiliary contacts. As the downward movement continues, the auxiliary movable contacts 17 move outwardly against the fixed auxiliary contacts 11 until the contact is broken, causing the formation of arcs between them. The continued downward movement of the bridging member causes the final rupture of the current and the extinguishment of the arcs.

The quenching of the arcs at the auxiliary contacts is rapidly and effectively accomplished due to the combined effect of various forces. The electromagnetic action tends to force the arcs outwardly and the provision of side plates or flanges 17b creates paths for the current to be forced outwardly from the rounded portions 11a of the contacts and thus permit the arc to be forced by the electromagnetic action outwardly to the outermost tip of the flanges 17b. The electromagnetic action also causes the path of the arc to move outwardly to the portions 12 of the auxiliary fixed contacts and move upwardly along the outer portion of these contacts until it reaches the rounded tip 13. This tip is a limiting position of the arc travel and results in the arc forming a path as indicated at 21 from the tips 13 to the tips or ends of the flanges 17b; and it should be appreciated that this arc is sub-divided into paths from the two flanges 17b of each auxiliary contact to the tips 13 of the auxiliary fixed contacts. This forcing of the arc to the outward position described and to tips of the co-operating auxiliary contacts by the electromagnetic field, together with the sub-division of the arc, results in such attenuation of the arc between limiting contact tips as to rapidly extinguish it. A further action occurs because as the arc is forced outwardly into fresh and cooler oil in the manner described, a blast of fresh oil is caused to move outwardly between the contacts as indicated by the arrows 22 and strike against the arc to further hasten the quenching of the arc.

Comparative tests have shown that the present improvement has very marked advantages in the respects previously described, as compared with the results obtained by the construction shown and described in my prior Patent #1,974,525.

Although a preferred embodiment of this invention has been described, it will be understood that various modifications may be made without departing from the scope of the invention.

The invention claimed is:

1. A circuit breaker comprising a movable conducting element, a fixed conducting element, an auxiliary conducting element movable relatively to and carried by said movable conducting element, said auxiliary conducting element having a contacting portion adapted to engage the inner face of the fixed conducting element and having a side portion extending outwardly and embracing a side of said fixed conducting element in the closed position of the breaker, and means for biasing said auxiliary element outwardly to cause said contacting portion to engage the inner face of said fixed conducting element and to cause said side portion to move outwardly relatively to said fixed conducting element upon the opening of the breaker.

2. A circuit breaker comprising a movable conducting element, a fixed conducting element, an auxiliary conducting element pivotally mounted on said movable conducting element, said auxiliary conducting element having a contacting portion adapted to engage the inner face of the fixed conducting element and having a side portion extending outwardly and embracing a side of said fixed conducting element in the closed position of the breaker, and a spring for biasing said auxiliary element outwardly to cause said contacting portion to engage the inner face of said fixed conducting element and to cause said side portion to move outwardly relatively to said fixed conducting element upon the opening of the breaker.

3. A circuit breaker comprising a movable conducting element, a fixed conducting element, an auxiliary conducting element movable relatively to and carried by said movable conducting element, said auxiliary conducting element having a contacting portion adapted to engage the inner face of the fixed conducting element and having a side portion extending outwardly and embracing a side of said fixed conducting element in the closed position of the breaker, and means for biasing said auxiliary element outwardly to cause said contacting portion to engage the inner face of said fixed conducting element and to cause said side portion to move outwardly relatively to said fixed conducting element upon the opening of the breaker.

3. A circuit breaker comprising a movable conducting element, a fixed conducting element, an auxiliary conducting element movable relatively to and carried by said movable conducting element, said auxiliary conducting element having a contacting portion adapted to engage the inner face of the fixed conducting element and having a side portion extending outwardly and embracing a side of said fixed conducting element in the closed position of the breaker, and means for biasing said auxiliary element outwardly to cause said contacting portion to engage the inner face of said fixed conducting element and to cause said side portion to move outwardly relatively to said fixed conducting element upon the opening of the breaker, said fixed conducting element having a portion projecting outwardly to cooperate with the tip of said side portion in carrying the arc at the time of rupture.

4. A circuit breaker comprising a movable conducting element, a fixed conducting element, an auxiliary conducting element movable relatively to and carried by said movable conducting element, said auxiliary conducting element having a central contacting portion adapted to engage the inner face of the fixed conducting element and having side portions extending outwardly and embracing opposite sides of said fixed conducting element in the closed position of the breaker, and means for biasing said auxiliary element outwardly to cause said contacting portion to engage the inner face of said fixed conducting element and to cause said side portions to move outwardly relatively to said fixed conducting element upon the opening of the breaker.

5. A circuit breaker comprising a movable conducting element, a fixed conducting element, an auxiliary conducting element movable relatively to and carried by said movable conducting element, said auxiliary conducting element having a central contacting portion adapted to engage the inner face of the fixed conducting element and having side portions extending outwardly and embracing opposite sides of said fixed conducting element in the closed position of the breaker, and means for biasing said auxiliary element outwardly to cause said contacting portion to engage the inner face of said fixed conducting element and to cause said side portions to move outwardly relatively to said fixed conducting element upon the opening of the breaker, said fixed conducting element having a portion projecting outwardly to cooperate with the tips of said side portions in carrying the arc at the time of rupture.

JOSEPH D. WOOD.
